DESIGN FOR AN OZONIZER

William A. Pardey, Portland, Oreg.

Application December 9, 1939, Serial No. 88,791

Term of patent 3½ years

To all whom it may concern:

Be it known that I, William A. Pardey, a citizen of the United States, residing at 6020 N. E. Glisan Street, city of Portland, in the county of Multnomah and the State of Oregon, have invented a new, original, and ornamental Design for an Ozonizer, of which the following is a specification, reference being had to the accompanying drawing, forming part thereof.

Fig. I is a plan view of the ozonizer, showing my new design.

Fig. II is a side elevational view thereof; and Fig. III is an end elevational view thereof.

I claim:

The ornamental design for an ozonizer, as shown.

WILLIAM A. PARDEY.
